(57) **CLAIM**

The ornamental design for an automotive mirror as shown and described.

DESCRIPTION

FIG. 1 is a top, front, right perspective view of an automotive mirror, in accordance with an embodiment;

FIG. 2 is a bottom, rear, right perspective view of the automotive mirror of FIG. 1;

FIG. 3 is a front view of the automotive mirror of FIG. 1;

FIG. 4 is a rear view of the automotive mirror of FIG. 1;

FIG. 5 is a left side view of the automotive mirror of FIG. 1;

FIG. 6 is a right side view of the automotive mirror of FIG. 1;

FIG. 7 is a top view of the automotive mirror of FIG. 1;

FIG. 8 is a bottom view of the automotive mirror of FIG. 1;

FIG. 9 is a top, front, right perspective view of an automotive mirror, in accordance with an embodiment;

FIG. 10 is a bottom, rear, right perspective view of the automotive mirror of FIG. 9;

FIG. 11 is a front view of the automotive mirror of FIG. 9;

FIG. 12 is a rear view of the automotive mirror of FIG. 9;

FIG. 13 is a right side view of the automotive mirror of FIG. 9;

FIG. 14 is a left side view of the automotive mirror of FIG. 9;

FIG. 15 is a top view of the automotive mirror of FIG. 9; and,

FIG. 16 is a bottom view of the automotive mirror of FIG. 9.

The ornamental design which is claimed is shown in solid lines in the drawings. The broken lines of equal length dashes in the drawings are for illustrative purposes and form no part of the claimed design. Broken lines formed by unequal length dashes (i.e., dash-dot) define bounds of the claimed design.
